I claim the ornamental design for a portable pedicure station, as shown and described.

DESCRIPTION

FIG. 1 is a front perspective view of the portable pedicure station of the present invention in a deployed position.

FIG. 2 is a rear perspective view of the portable pedicure station of the present invention in a deployed position.

FIG. 3 is a front elevational view of the portable pedicure station of the present invention in a deployed position.

FIG. 4 is a rear elevational view of the portable pedicure station of the present invention in a deployed position.

FIG. 5 is a right side elevational view of the portable pedicure station of the present invention in a deployed position.

FIG. 6 is a left side elevational view of the portable pedicure station of the present invention in a deployed position.

FIG. 7 is a top view of the portable pedicure station of the present invention in a deployed position; and,

FIG. 8 is a bottom view of the portable pedicure station of the present invention in a deployed position.

The broken lines shown along the bottom of the portable pedicure station form no part of the claimed design.
